WELL PACKER AND TESTING TOOL
COMBINATION

Thomas B. Slick, Robinson W. Brown, and Hugh E. Metcalf, San Antonio, Tex., assignors to The Institute of Inventive Research, San Antonio, Tex., a trust estate of Texas

Application July 22, 1950, Serial No. 175,416

18 Claims. (Cl. 166—10)

1

This invention relates in general to a packer and testing tool for wells. Its general object is the provision of a packer which is especially adapted for use as a part of a testing tool, and the provision of a testing tool combination including such packer.

A further object of this invention is to provide a packer which may be set at any depth above the bottom of the well without the necessity of the use of a tail pipe extending from the packer to the bottom of the well.

Another object is to provide a drill stem testing tool which will make it possible for the drill stem to be run into the well dry, which will make it unnecessary for liquid or gas to be caused to flow down through the drill stem to actuate or release the packer or open the valve to test the well and which will eliminate necessity for electrical connections to the surface of the earth.

Another object is to provide a packer arrangement in which any number of packers desired may be employed in tandem, to be set simultaneously.

Another object is to provide a packer operable to set or release without causing any movement of the drill stem or flow of liquid, gas, or electricity from the surface of the ground.

Another object is to provide a drill stem tester in which all fluid passages are sealed positively until the operator is ready to open the same for the purpose of testing the well.

Other objects and advantages of this invention will become apparent from the following description taken in connection with the accompanying drawing wherein is set forth by way of illustration and example one embodiment of the invention.

In the drawing:

Figure 1 is a view in longitudinal cross section through a drill stem testing tool constructed in accordance with this invention, the same being illustrated in a well but before the tool has been set or a test made.

Figure 2 is a view on an enlarged scale showing a fragmentary longitudinal cross section of the structure illustrated in Figure 1, but with the parts in positions which they occupy after the setting of the tool and the expansion of the packer.

Figure 3 is a view similar to Figure 2, illustrating an extension thereof to show the lower end of the structure which does not appear in Figure 2, with the parts in the positions they occupy during the making of a test of a well.

Figure 4 is a horizontal cross section taken along the line 4—4 of Figure 2, and illustrating

the expandible end plate structure employed at each end of the packing sleeve, the parts being shown in the positions which they occupy when the packing sleeve has been expanded.

Figure 5 is a view similar to Figure 2, but taken at a position higher up on the tool and illustrating the parts in the positions which they occupy after a test has been made and the packing sleeve contracted.

Figure 6 is a view taken along the line 6—6 of Figure 5, and showing the parts illustrated in Figure 4 but when the same are in the positions which they occupy with the packing sleeve contracted.

Figure 7 is a horizontal cross section taken along the line 7—7 of Figure 3.

Figure 8 is a fragmentary view similar to the upper portion of Figure 5, but showing the action of the go-devil in setting off the explosive charge for causing the release of the packing sleeve, when such go-devil happens to drop in a position at right angles to that illustrated in Figure 5.

Figure 9 is an enlarged fragmentary portion of the structure illustrated in Figure 8.

Figure 10 is an enlarged fragmentary cross section showing the action of the go-devil illustrated in the upper portion of Figure 5 and in Figure 8 when the same is passing down through the drill stem past a tool joint.

Referring now more in detail to the drawing, the numeral 1 indicates the lower end portion of a drill stem on which the tool constructed in accordance with this invention is adapted to be run into a well. On the lower end of the drill stem there is fixed a fitting which may be referred

to as a "substitute" 2 having a bore therethrough the upper end portion of which is tapered downwardly as shown at 3, and the lower end portion of which is flared as illustrated at 4. To the lower end of the substitute 2 is threaded another substitute 5 likewise having a bore therethrough, the upper end of the bore terminating in an upwardly facing shoulder 6 on which is adapted to rest a ring 7 within the lower flared portion 4 of the substitute 2. This ring 7 constitutes an actuating part and is adapted to bear against the upper end of the firing pin 8 and actuate the same in the manner hereinafter to be described so as to initiate the explosion of a cap 9 which will in turn cause the ignition of the explosive charge 10. This explosive charge 10 is located in an explosive chamber which is actually a portion of a conduit in which is normally located a plug 11 intended to plug the con-

duit against flow therethrough.

This conduit has a branch 11a above the plug 11, and below the plug is connected to a downwardly extending tubular member which in this instance is located on the exterior of the tool assembly as shown at 12. Tube 12 provides a conduit for the release of the inflating fluid of the packing sleeve as hereinafter set forth.

Threaded into the lower end portion of the substitute 5 is still another fitting 13 having an enlarged bore 14 therethrough. Threadedly engaging the lower end of this fitting 13 is a fitting which may be termed a packing mandrel 15 having a tubular extension of reduced external diameter 16 extending upwardly therefrom entirely through the enlarged bore 14 of the fitting 13 but of smaller diameter than the bore so as to provide a pressure chamber, illustrated as an annular chamber between the tubular extension 16 and the inner wall of bore 14.

Extending from the pressure chamber just referred to, downwardly through the fitting 15 is a conduit 17 which opens on the exterior of the fitting or packer mandrel 15 at a point intermediate its ends, which point is adapted to be within the packer sleeve of the packer portion of this tool. A lateral branch 18 leading from the conduit 17 connects with the tubing 12 so as to complete the inflation release conduit for releasing the inflating fluid of the packer.

The mandrel 15 is provided with a lower cylindrical external surface 19 for the purpose of receiving the packer sleeve 20 formed of a suitable flexible material such as rubber or the like.

Located in the upper end of the annular chamber formed between the fitting 13 and the tubular extension 16, is a back-up ring 21 and an annular chamber 22 therebelow which may be termed "an explosive chamber" as it is adapted to receive a slow burning explosive charge. Below this explosive chamber and separating it from the lower part of the annular space is an annular piston 23 which is slidable downwardly through the annular space. Thus, there is provided a pressure chamber adapted to receive an explosive charge therein and having conduit 17 connected thereto.

The explosive charge in the explosive chamber 22 is adapted to be fired by means of a firing pin 24, including an actuating part illustrated as an enlarged head, which in turn causes the detonation of a detonating cap 25. Below the piston 23 is a chamber 26 adapted to contain a fluid for the purpose of inflating the packer sleeve 20, and it will be understood that when the firing pin 24 is forced downwardly to cause the explosion of the explosive in the chamber 22, this slow burning explosive will force the annular piston 23 downwardly and will force the inflating fluid from the annular chamber 26 below the piston, downwardly through the check valves 27 and the conduit 17 into the space outside of the mandrel 15 and within the packer sleeve 20. Thus, the piston 23 provides a means whereby when the explosive in the chamber 22 is set off, the explosive chamber is enlarged and the fluid for inflating the sleeve 20 is forced in behind such sleeve by virtue of the contraction or reduction in size of the chamber holding such inflation fluid. Back flow of this inflating fluid from behind the sleeve 20 is prevented by means of the check valves 27, of which a number are shown for purposes of safety so that if one fails the others will take the load.

The lower end of the mandrel for the packer sleeve 20 is provided by a fitting or substitute 28

which is threaded into the lower end of the fitting 15, and is provided with a bore forming a continuation of the bore through the fitting 15.

The ends of the packer sleeve 20 may be held in sealed engagement with the exterior of the mandrel on which this sleeve is mounted, at axially spaced positions and along circumferential lines, by any suitable means. One such means comprises the split rings 29 and 30 which are adapted to be held in clamping engagement against the end portions 31 and 32 of the packer sleeve 20 by means such as the threaded holding nuts 33 and 34 respectively. Interposed between the ends of the nuts 33 and 34, respectively, and the adjacent portions of the packer sleeve 20, are expandable rings or dams 35 and 36, which are shown more in detail in Figures 4 and 6. As illustrated in those figures, these expandable rings are intended to expand when the sleeve 20 expands and provide supports for the end portions of the sleeve 20 so as to prevent the extrusion of this sleeve in a longitudinal direction. This ring 35 is made up of interfitting segments as clearly illustrated in Figures 4 and 6, and ring 36 is of the same construction.

The lower end portion of the bore through the fitting 28 is provided with longitudinal slots 37 in its sides, any desired number of such slots being provided. These slots are preferably in communication with the main bore throughout their entire length.

Threaded into the lower end of the fitting 28 is a shoe 38 having a bore along its axis part way therethrough which bore forms a continuation of the bore through the fittings 15 and 28. At its upper end this shoe 38 is provided with a tapered counterbore 39 adapted to receive a short tapered bushing 40, the taper between these parts being such that they will not stick together. The bushing 40 provides an explosive chamber adapted to receive an explosive charge 41, the lower end of the explosive chamber being closed by means of a plug or plate 42. Just above the explosive chamber just mentioned, the bore in the fitting 28 is provided with a bridge 43, in which is formed a bearing for a firing pin 44. Depression of this firing pin 44 will initiate the explosion of the explosive 41.

Adjacent its lower end, the shoe 38 is provided with a lateral bore 45, the outer end of which is closed by a plug 46. Connecting the bottom end of the shoe 38 with the lateral bore 45 inwardly of the plug 46 is an eccentric longitudinal bore 47 having a valve seat fitting 48 inserted into its lower end and welded or otherwise secured therein. A check valve 49 is adapted to be disposed within the conduit 47 above the seat fitting 48 and to seat against the valve seat provided on the upper end of this fitting so as to prevent flow from the interior of the shoe 38 outwardly through the passageways 45 and 47, but so as to permit flow freely from below the shoe in through said passageways and into the tool proper.

It is to be noted that the firing pin 44 is disposed on the axial center of the tool, whereas the firing pin 24 is disposed in a position more remote from the axial center of the tool and the firing pin 8 is disposed still further from the axial center of the tool.

For the purpose of actuating the firing pin 24, there is provided a go-devil in the form of a tapered bushing 50 which has an opening completely therethrough, the opening in this instance being illustrated as tapered from the upper end

of this go-devil downwardly, and the lower end of the opening through this bushing being of substantially the same size as the central passageway through the fittings 15 and 28.

For the purpose of actuating the firing pin 44 there is provided a go-devil in the form of a slender rod 51 adapted to pass downwardly through the central passageway in the fittings 15 and 28, as well as through the tapered hollow go-devil 50, to engage the firing pin 44. It is to be noted that with this go-devil in place within the tool as shown in figure 3, it is flanked on opposite sides by the slots 37 so that flow through the tool past this go-devil is unobstructed.

For the purpose of actuating the firing pin 8, there is provided a go-devil having a body 52 which may if desired have a tapered lower end as illustrated, and which at an appropriate position is provided with a slot therethrough in which are disposed a pair of dogs 53 pivoted on a pivot 54 carried by the go-devil 52. These dogs 53 are urged toward expanded position at all times by means of a spring 55, but are permitted to retract so that the go-devil may be passed downwardly through the drill stem. These dogs are rounded on their outer surfaces so that they will readily pass through tool joints forming part of the drill stem, in the manner illustrated in Figure 10, but when the go-devil 52 reaches the position illustrated in Figure 5 or Figure 8, these dogs 53 will expand into the flaring lower portion 4 of the substitute 2, and their lower ends will engage the ring 7 and force it downwardly. It will be appreciated if the ring 7 will be forced downwardly regardless of the rotary position of the go-devil 52, two such positions being illustrated in Figures 5 and 8 respectively, the downward motion of the ring 7 will cause the depression of the firing pin 8 which will in turn detonate the cap 9 and cause the firing of the explosive charge 10.

Preferably the explosive charges 10 and 41 are of the type known as "shaped" charges, or charges so shaped as to provide a force directed principally in one direction, this phenomenon being ordinarily referred to as the "Monroe" effect. It will readily be seen that the firing of the explosive charge 10 will result in the destruction of the plug 11, which will permit the fluid with which the packer sleeve 28 is inflated to flow upwardly through the lower portion of the conduit 17, outwardly through the branch 18, upwardly through the tubing 12, then upwardly past the location of the plug 11 and outwardly through the branch conduit 11a. This will, of course, permit the packer sleeve 28 to retract.

Likewise, the firing of the explosive charge 41 will cause the perforation of the disc or plate 42 and thereby open the passageway upwardly through the shoe 38, permitting fluid to flow from the formation upwardly past the check valve 49 and up through the passageway in the fittings 15 and 28 into the drill stem.

In the course of running a drill stem test, it is sometimes necessary to stop any upward flow through the drill pipe as well as around the outside of the pipe to prevent a blowout of the well. The outside flow around the device just described is stopped by the inflated packer, but after discharge of the explosive charge 41 the tool will be open for upward flow through its interior. For the purpose of enabling an operator to shut off this inside flow when desired, the following described structure is provided:

The threaded joint between the substitute 2 75

and the substitute 5 is in the form of a straight thread as distinguished from a tapered thread, this threaded joint being indicated at 54a. The pin portion of this threaded joint is on the substitute 2 and the lower end of this pin portion is provided with an unthreaded cylindrical section 55 which is adapted to fit within a similarly shaped portion in the substitute 5 and be sealed therein by means of suitable seal rings 56. Adjacent its shank end, the pin of the substitute 2 is provided with a circumferential groove 57, the upper extremity of this groove 57 being adapted to register with an opening in the box portion of the joint when the joint is in full threaded engagement so that a pin 58 inserted through such opening may enter within the upper portion of the groove 57. It will be seen that by this arrangement there is provided a joint which may be partly unscrewed but the extent of the unthreading of the joint will be limited by the pin 58 in its engagement with the groove 57. Furthermore, it will be seen that the partial unthreading of this joint will not serve to break the seal between the two parts joined together, because the seal rings 56 will continue to engage the cylindrical portion 55 and provide a seal between the parts.

In the substitute 5 there is provided a short distance below the shoulder 6 an annular enlargement of the bore as indicated at 59, this enlargement being sufficient to house the flapper valve member 60 in a vertical position outside of the regular path of flow through the bore of this fitting. This flapper valve member 60 is hinged at its upper end 61 and it is adapted when swung about this hinged connection to a horizontal position to seat against the shoulder 62 at the upper extremity of the enlarged portion 59.

Normally this flapper valve will be held in its lowermost position by means of a latch or hook 63 which is pivotally mounted on the substitute at 64 and which has its opposite end 65 held down by a push rod 66 so as to hold the latch 63 in engagement with the lower edge of the flapper valve 60 and retain the flapper valve in vertical position as illustrated. The upper end of the push rod 66 is held down normally by a plunger 67 which is engaged by the lower extremity of the pin on the substitute 2 when that substitute is in full threaded engagement with the threaded joint 54. A spring 68 in the space below the plunger 67 constantly urges the plunger and the push rod 66 upwardly.

It will be seen that when the joint between the substitutes 2 and 5 is in full threaded engagement the plunger 67 and push rod 66 will be held down thereby holding the latch 63 in engagement with the flapper valve 60 and preventing this flapper valve from closing. On the other hand, if it be desired at any time to stop upward flow through the tool, it is only necessary to back off the threaded connection 54a to the extent permitted by the pin 58, whereupon the plunger 67 and push rod 66 will be allowed to move upwardly permitting the latch 63 to disengage from the flapper valve 60 so that this flapper valve can close against the seat 62 and stop upward flow through the tool.

Preferably the threaded joint 54a will be formed with a left-hand thread, or, more properly stated, with a thread of the opposite pitch from the threads of the other joints of the string of pipe. This will make possible the breaking of the threaded connection 54a if it should be tight, without danger of unthreading the pipe at some other point.

Normally, it will not be found necessary to provide a spring for closing the flapper valve 60 because the turbulence due to flow upwardly through the tool will serve to swing the flapper valve out of its recess and move it to its seat. If, however, it be desired to provide for the closing of the flapper valve even when no flow exists through the tool or when the flow is only very slight, a suitable spring may be provided for moving the flapper valve from its vertical to its seated position.

In operation, it will be understood that the tool may be lowered into the well in the condition illustrated in Figure 1 until it reaches a location where it is desired to set the tool and make a test of the formation. When such location has been reached, the tapered, hollow go-devil 50 will be dropped in through the drill stem, which meanwhile is free of liquid, and in which, for that reason, the pressure existing is little different from that of the atmosphere at the surface of the ground. When the go-devil 50 reaches the tool it will land on the firing pin 24 in the manner illustrated in the upper portion of Figure 2 and in the mid-portion of Figure 5, and will cause the firing of the explosive charge in the annular explosive chamber 22. This charge being a slow burning charge, will force the piston 23 downwardly and will force the inflating fluid in the chamber 26 through the check valves 27 and the passageway 17 into the space behind the packer sleeve 20, thereby expanding this packer sleeve into sealing engagement with the walls of the well.

It will be assumed that the expansion of the packer sleeve 20, in the manner just described, serves to seal off the formation to be tested from the remainder of the well, and it will be noted that the expansion of this packer sleeve will have been accomplished without the necessity for any electrical connections down through the drill stem, and without the necessity for forcing any gas or liquid down through the drill stem. The drill stem will remain substantially empty and at a low pressure so that formation pressure, when admitted, can readily force a sample of the production of the formation into the drill stem.

The next step is to drop into the well the go-devil 51 which, when landed in the position illustrated in Figure 3, causes the firing of the explosive charge 41, which in turn destroys the effectiveness of the plug 42. When this occurs, the tool will be open to receive into the drill stem the production of the formation to be tested.

When the formation has been allowed to produce through the tool for such period of time as may be desired, flow may be shut off by appropriate controls at the surface and the packer sleeve 20 contracted by dropping into the well the go-devil 52 which, as above described, causes the actuation of the firing pin 8 and the firing of the explosive charge 10. The firing of this charge 10 destroys the effectiveness of the plug or closure 11 which theretofore prevented release of the inflating fluid from behind the packer sleeve 20 through the fluid release conduit which is provided principally by the tubing 12 as supplemented by the lower portion of the conduit 17, the branch conduit 18, and the conduit 11a.

With the packer sleeve 20 thus contracted, the tool is free to be withdrawn from the well, and this may readily be accomplished in the usual fashion.

It will be appreciated that by the device dis-

closed there has been provided a structure capable of carrying out and accomplishing all of the objects and advantages sought by this invention. It will further be seen that the packer, while especially adapted to and forming an integral part of the testing tool, may be used without the testing tool feature for those uses in which a packer may be needed but no testing is required. It is further apparent that two or more packing sleeves such as disclosed may be used in tandem and inflated and released simultaneously if desired for safety or for the purpose of sealing off above and below an intermediate formation, and that the intake opening into the testing tool may be located at any desired point along the composite body of the tool. It is to be understood that the device illustrated and described is by way of example only and is not to be taken as a limitation upon the scope of this invention, because it will be appreciated that variations in arrangement, size and configuration of parts and substitution of equivalents may be had all within the spirit and scope of the appended claims.

The invention having been described, what is claimed is:

1. A drill stem tester comprising a hollow body adapted to be connected to a drill stem or the like and having an interior portion for receiving a fluid sample, inflatable packing surrounding said body intermediate its ends and adapted when inflated to seal off a formation to be tested, said body having a passageway connecting the sample receiving portion of its interior with its exterior at a position exposed to the formation to be tested, an imperforate plug in said passageway preventing fluid flow into said interior portion of said body, an inwardly opening check valve in said passageway, a packing inflator for said packing carried by said body and connected to said packer, a plug destroyer in said body arranged to destroy said plug when actuated to permit a fluid sample to flow into said body, an inflation release carried by said body and connected to said packing, and mechanical means adapted to be lowered into said body through a drill stem attached thereto to selectively actuate said inflator, plug destroyer, and inflation release.
2. A drill stem tester comprising a hollow body for receiving a fluid sample and adapted to be connected to a drill stem or the like, inflatable packing surrounding said body intermediate its ends and adapted when inflated to seal off a formation to be tested, said body having a passageway connecting its interior wherein the sample is to be received with its exterior at a position exposed to the formation to be tested, a plug sealing said passageway from fluid flow therethrough, an inwardly opening check valve in said passageway, a packing inflator including an explosive charge for inflating said packing, said inflator being carried by said body and connected to said packing, a plug destroyer in said body arranged to destroy said plug when actuated, an inflation release carried by said body and connected to said packing, and mechanical means adapted to be lowered into said body through a drill stem attached thereto to selectively actuate said inflator, plug destroyer, and inflation release.
3. A drill stem tester comprising a hollow body adapted to be connected to a drill stem or the like, inflatable packing surrounding said body intermediate its ends and adapted when inflated to seal off a formation to be tested, said body

having a passageway connecting its interior with its exterior at a position exposed to the formation to be tested, a plug and an inwardly opening check valve in said passageway, a packing inflator for said packing carried by said body and connected to said packing, a plug destroyer in said body arranged to destroy said plug when actuated, an inflation release carried by said body and connected to said packing and including an explosive charge, and mechanical means adapted to be lowered into said body through a drill stem attached thereto to selectively actuate said inflator, plug destroyer, and inflation release.

4. A drill stem tester comprising a hollow body adapted to be connected to a drill stem or the like, inflatable packing surrounding said body intermediate its ends and adapted when inflated to seal off a formation to be tested, said body having a passageway connecting its interior with its exterior at a position exposed to the formation to be tested, a plug and an inwardly opening check valve in said passageway, a packing inflator for said packing carried by said body and connected to said packing, a plug destroyer in said body arranged to destroy said plug when actuated, and including an explosive charge, an inflation release carried by said body and connected to said packing, and mechanical means adapted to be lowered into said body through a drill stem attached thereto to selectively actuate said inflator, plug destroyer, and inflation release.

5. A drill stem tester comprising a hollow body adapted to be connected to a drill stem or the like, inflatable packing surrounding said body intermediate its ends and adapted when inflated to seal off a formation to be tested, said body having a passageway connecting its interior with its exterior at a position exposed to the formation to be tested, a plug and an inwardly opening check valve in said passageway, a packing inflator for said packing carried by said body and connected to said packing, a plug destroyer in said body arranged to destroy said plug when actuated, an inflation release carried by said body and connected to said packing, and mechanical means adapted to be lowered into said body through a drill stem attached thereto to selectively actuate said inflator, plug destroyer, and inflation release, said packing inflator and inflation release each including an explosive charge.

6. A drill stem tester comprising a hollow body adapted to be connected to a drill stem or the like, inflatable packing surrounding said body intermediate its ends and adapted when inflated to seal off a formation to be tested, said body having a passageway connecting its interior with its exterior at a position exposed to the formation to be tested, a plug and an inwardly opening check valve in said passageway, a packing inflator for said packing carried by said body and connected to said packing, a plug destroyer in said body arranged to destroy said plug when actuated, an inflation release carried by said body and connected to said packing, and mechanical means adapted to be lowered into said body through a drill stem attached thereto to selectively actuate said inflator, plug destroyer, and inflation release, said packing inflator, inflation release, and plug destroyer, each including an explosive charge.

7. A packer comprising a body having a pressure chamber formed therein adapted to receive

an explosive charge, and a conduit connecting said pressure chamber to the exterior surface of said body intermediate its ends, an expansible sleeve of packing material surrounding a zone of said body and sealed to said body along spaced circumferential lines on opposite sides of the outer end of said conduit, and means carried by said body for initiating the explosion of an explosive charge in said pressure chamber.

8. A packer comprising a body having an annular chamber formed therein, and a conduit connecting said annular chamber to the exterior surface of said body intermediate its ends, an expansible sleeve of packing material surrounding a zone of said body and sealed to said body along spaced circumferential lines on opposite sides of the outer end of said conduit, means carried by said body for initiating the explosion of an explosive charge in said annular chamber, and a check valve means in said conduit preventing flow towards said annular chamber.

9. A packer comprising a body having a pressure chamber formed therein adapted to receive an explosive charge and a conduit connecting said pressure chamber to the exterior surface of said body intermediate its ends, an expansible sleeve of packing material surrounding a zone of said body and sealed to said body along spaced circumferential lines on opposite sides of the outer end of said conduit, means carried by said body for initiating the explosion of an explosive charge in said pressure chamber, and means in said conduit for preventing back flow of fluid therethrough.

10. A packer comprising a body having an explosive chamber formed therein, a chamber for packer inflating fluid communicating with said explosive chamber, and a conduit connecting said chamber for packer inflating fluid with the exterior surface of said body intermediate its ends, an expansible sleeve of packing material surrounding a zone of said body and sealed to said body along spaced circumferential lines on opposite sides of the outer end of said conduit, a piston in said chamber for packer inflating fluid dividing the explosive chamber from said chamber for packer inflating fluid and slidably in said chamber for packer inflating fluid to enlarge the explosive chamber and contract the chamber for packer inflating fluid, means carried by said body for initiating the explosion of an explosive charge in said explosive chamber, and means in said conduit for preventing back flow of fluid from within said packing sleeve.

11. A packer comprising a body having a pressure chamber formed therein adapted to receive an explosive charge and a conduit connecting said pressure chamber to the exterior surface of said body intermediate its ends, an expansible sleeve of packing material surrounding a zone of said body and sealed to said body along spaced circumferential lines on opposite sides of the outer end of said conduit, means carried by said body for initiating the explosion of an explosive charge in said pressure chamber, means providing a conduit for the escape of fluid from the space within said packing sleeve between said seal lines, a closure in said last mentioned conduit, explosive means carried by the body for destroying the effectiveness of said closure, and means carried by said body for initiating the explosion of said last mentioned explosive means.

12. A packer comprising a body, an expansible sleeve of packing material surrounding a zone of said body and sealed to said body along spaced

circumferential lines, an inflator carried by said body and in communication with the space between said body and sleeve intermediate said seal lines for inflating and expanding said packer sleeve, means providing a conduit for the escape of fluid from the space within said packing sleeve between said seal lines, a closure in said conduit, and explosive means carried by said body for destroying the effectiveness of said closure, and means carried by said body for initiating the explosion of said explosive means.

13. A packer adapted to be disposed in a well comprising a body having a pressure chamber formed therein adapted to receive an explosive charge and a conduit connecting said pressure chamber to the exterior surface of said body intermediate its ends, an expansible sleeve of packing material surrounding a zone of said body and sealed to said body along spaced circumferential lines on opposite sides of the outer end of said conduit, means carried by said body for initiating the explosion of an explosive charge in said pressure chamber, said initiating means having a part exposed to communication from a point above the packer when the packer is disposed in a well, and a go-devil adapted to be dropped from above said packer and shaped to act upon said exposed part and actuate the explosive initiating means when so dropped.

14. A packer comprising a body having a pressure chamber formed therein adapted to receive an explosive charge and a conduit connecting said pressure chamber to the exterior surface of said body intermediate its ends, an expansible sleeve of packing material surrounding a zone of said body and sealed to said body along spaced circumferential lines on opposite sides of the outer end of said conduit, means carried by said body for initiating the explosion of an explosive charge in said pressure chamber, means providing a conduit for the escape of fluid from the space within said packing sleeve between said seal lines, a closure in said conduit, explosive means carried by the body for destroying the effectiveness of said closure, means carried by said body for initiating the explosion of each of said explosive means, said initiating means having parts exposed to communication with the space above the packer when the packer is disposed in a well, and two differently shaped go-devils adapted to be dropped from above said packer, one of said go-devils being shaped to act upon the exposed part of one of said initiating means and the other of said go-devils being shaped to act upon the exposed part of the other of said initiating means.

15. A packer comprising a body having a pressure chamber formed therein adapted to receive an explosive charge and a conduit connecting said pressure chamber to the exterior surface of said body intermediate its ends, an expansible sleeve of packing material surrounding a zone of said body and sealed to said body along spaced circumferential lines on opposite sides of the outer end of said conduit, means carried by said body for initiating the explosion of an explosive charge in said pressure chamber, means providing a conduit for the escape of fluid from the space within said packing sleeve between said seal lines, a closure in said conduit, explosive means carried by the body for destroying the effectiveness of said closure, and means carried by said body for initiating the explosion of said last mentioned explosive means, and an explosive charge in said first mentioned

pressure chamber which is of slower burning characteristics than the explosive means for destroying the effectiveness of said closure.

16. A packer comprising a body having a hollow end, two explosive chambers formed therein adjacent said hollow end, an inflating fluid reservoir connected in pressure receiving relationship with one of said chambers, and a conduit connecting said reservoir to the exterior surface of the body intermediate its ends, an expansible sleeve of packing material surrounding a zone of said body and sealed to said body along spaced circumferential lines on opposite sides of the outer end of said conduit, means providing a conduit for the escape of fluid from the space within said packing sleeve between said seal lines, said last mentioned conduit having a part thereof located adjacent the second of said chambers, a closure in said last mentioned conduit adjacent said second chamber in position to be rendered ineffective by explosion of a charge in said second chamber, a firing pin for each of said chambers having actuating parts exposed within said hollow end of the body at different lateral distances from the longitudinal axis of the hollow end of said body, a go-devil adapted to be dropped into said hollow end and actuate the firing pin nearer the axis, and another go-devil having expanding parts adapted to be dropped into said hollow end and actuate the firing pin farther from the axis.

17. A packer comprising a body having a hollow end, two explosive chambers formed therein adjacent said hollow end, an inflating fluid reservoir connected in pressure receiving relationship with one of said chambers, and a conduit connecting said reservoir to the exterior surface of the body intermediate its ends, an expansible sleeve of packing material surrounding a zone of said body and sealed to said body along spaced circumferential lines on opposite sides of the outer end of said conduit, means providing a conduit for the escape of fluid from the space within said packing sleeve between said seal lines, said last mentioned conduit passing adjacent the second of said chambers, a closure in said last mentioned conduit adjacent said second chamber in position to be rendered ineffective by explosion of a charge in said second chamber, a firing pin for each of said chambers having actuating parts exposed within said hollow end of the body at different lateral distances from the longitudinal axis of the hollow end of said body, a go-devil adapted to be dropped into said hollow end and actuate the firing pin nearer the axis, and another go-devil having expanding parts adapted to be dropped into said hollow end and actuate the firing pin farther from the axis, a body of liquid in said fluid reservoir, a relatively slow burning explosive in said first chamber, and a relatively fast burning explosive in said second chamber.

18. A drill stem tester comprising a hollow body adapted to be connected to a drill stem or the like, inflatable packing surrounding said body intermediate its ends and adapted when inflated to seal off a formation to be tested, said body having a passageway connecting its interior with its exterior at a position exposed to the formation to be tested, a plug and an inwardly opening check valve in said passageway, a packing inflator for said packing carried by said body and connected to said packing, a plug destroyer in said body arranged to destroy said plug when actuated, an inflation release carried

by said body and connected to said packing and including an explosive charge, mechanical means adapted to be lowered into said body through a drill stem attached thereto to selectively actuate said inflator, plug destroyer, and inflation release, a valve adapted to close the interior of said body against upward flow, a detent for holding said valve open, and mechanical means for releasing said detent.
